CLAIM

The ornamental design for a camper toy, as shown and described.

DESCRIPTION

FIG. 1 is a first perspective view of a camper toy showing our new design.

FIG. 2 is a second perspective view thereof.

FIG. 3 is a third perspective view thereof.

FIG. 4 is a front view thereof.

FIG. 5 is a back view thereof.

FIG. 6 is a right side view thereof.

FIG. 7 is a left side view thereof.

FIG. 8. is a top view thereof; and,

FIG. 9. is a bottom view thereof.

The broken lines in the drawings depict portions of the camper toy that form no part of the claimed design.
